UNITED STATES PATENT OFFICE.

JOHN ANDERSON, OF PHILADELPHIA, PENNSYLVANIA.

CAN-OPENER.

1,170,386.

Specification of Letters Patent. Patented Feb. 1, 1916.

Application filed June 24, 1915. Serial No. 36,019.

To all whom it may concern:

Be it known that I, JOHN ANDERSON, a citizen of the United States, residing in the city and county of Philadelphia, State of Pennsylvania, have invented a new and useful Can-Opener, of which the following is a specification.

My invention relates to a new and useful can opener and consists of a blade having 10 curved cutting edges converging downwardly from adjacent the ends of the body to meet in a point approximately at the median line of the body so that when the blade is presented to a can and forced thereinto, a long cut is made in the can where applied.

It further consists of other features all as will be hereinafter set forth.

For the purpose of illustrating my invention, I have shown in the accompanying drawing one form thereof which is at present preferred by me, since the same will give in practice satisfactory and reliable results, although it is to be understood that 25 the various instrumentalities of which my invention consists can be variously arranged and organized and that my invention is not limited to the precise arrangement and organization of these instrumentalities as here- 30 in shown and described.

Figure 1 is a perspective view of a can opener embodying my invention. Fig. 2 is a vertical sectional view showing the device when applied to a can. Fig. 3 is a sectional view on line α — α Fig. 2.

Similar numerals of reference indicate corresponding parts in the figures.

Referring to the drawings, 1 designates a head or body preferably of semicircular 40 form to conform to the shape of a can. Suitably connected with the body as by pins or rivets 2 is a curved blade 3, the upper portion of which extends substantially from one end 4 thereof to the other end 5. The cutting edges 6 and 7 of the blade extend downwardly and rearwardly in a curve and meet to form a point 8 situated at substantially the median line of the body 1.

Extending outwardly at the upper portion 50 of the blade is a semi-circular cleat or abutment 9 which, as here shown, is formed of a strip continuous from end to end of the body 1 but may be otherwise constructed.

Between the body and the strip the upper 55 portion of the blade is situated and is secured to the body as by pins or rivets 10.

To insure the proper insertion of the blade 2 into the can I have provided a guide, which consists of the bar 11 which is carried by the abutment 9 at substantially the median line of the blade and which is suitably spaced therefrom to permit passage of the wall of the can therebetween, the bar terminating at or near the point 8.

Suitably connected with the body 1 is a 65 rod 12 having the cross handle 13, one end of which is provided with a nail lifter or claw 14 and the opposite end is provided with a hammer head 15.

It will be understood that the device is 70 made in different sizes for different sized cans so that when the blade is inserted it will serve to sever a sufficient amount of the top to permit the removal of the contents.

The operation of the device is as follows:—The operator grasping the cross handle 12 places the point 8 at the edge of the top of the can to be opened and with the end of the guide bar 11 in position to pass down the outside of the can. By pressing downwardly the point easily punctures or passes through the top and the further downward pressure causes the curved cutting edges to cut the top adjacent the edges of the can around the top, equal to the 85 amount of the spread of the cutting edges, until the cleat 9 contacts with the top edge of the can when further downward movement is stopped positively by said exterior cleat while the head 3 is prevented from bending severely the cut out portion of the can down into the latter. The bar 11 meanwhile has passed downwardly on the outside of the can.

It will be noted that by the construction 95 of the blade, it will be situated close to the inside of the wall of the can, so that the contents thereof are not injured and it will be further understood that the length from the point 8 to the shoulder 9 is proportioned 100 so that the bottom of the can is not punctured by the blade. As the device is being removed from the cut can, by slightly tilting or inclining it the blade raises the severed cut portion of the top to permit the easy removal of the contents. Furthermore, by placing the can with the blade therein in horizontal or somewhat horizontal position with the back of the blade lowermost, said blade acts as a scoop so that in withdrawing it from the can, the contents of the can, if of solid or partly solid nature, such as 105 110

salmon, lobster, meats, etc., may be drawn out of the can by said blade or scoop in a convenient manner. The extractor or claw can be conveniently used to remove nails from boxes containing the cans.

It will now be apparent that I have devised a novel and useful construction of a combined can opener and tool which embodies the features of advantage enumerated as desirable in the statement of the invention and the above description, and while I have, in the present instance, shown and described preferred embodiments thereof which will give in practice satisfactory and reliable results, it is to be understood that the same are susceptible of modification in various particulars without departing from the spirit or scope of the invention or sacrificing any of its advantages.

Copies of this patent may be obtained for five cents each, by addressing the "Commissioner of Patents, Washington, D. C."

Having thus described my invention, what I claim as new and desire to secure by Letters Patent, is;—

A can opener composed of a blade, a handled head, and a cleat, said members being firmly connected, and a handle rising from and fixed to said head, said head being on the inner side of the upper end of the front of said blade, and said cleat being on the upper end of the back of said blade, said cleat being adapted to set-out said guide from said blade and to form a positive stop for the descent of said blade and said head by engagement with the top edge of the can.

JOHN ANDERSON.
